UNITED STATES PATENT OFFICE.

JAMES F. EGGLESTONE, OF YOUNGSTOWN, OHIO.

SCORE-SHEET HOLDER FOR GOLF CLUBS.

Application filed June 2, 1924. Serial No. 717,348.

This invention relates to improvements in score tabulating mechanisms.

The primary object of this invention is the provision of improved means compactly associated with a golf club for maintaining the score or record of games of an individual or individuals which are participating in a game as partners or opponents.

A further and important object of this invention is the provision of an improved golf club having score recording means associated with the handle or shank portion thereof in a compact and effective arrangement, so as to permit ordinary use of the golf club, without detracting in any manner from the efficiency of playing therewith.

A further object of this invention is the provision of score tabulating means located within a pocket formed in the handle of a golf club, preferably the "putter", so that it is at all times visible and accessible for the placing of a score thereon, or the reading of a score therefrom, without inconvenience.

Other objects and advantages of this invention will be apparent during the course of the following detailed description.

In the accompanying drawings, forming a part of this specification, and wherein similar reference characters designate corresponding parts throughout the several views,

Figure 1 is a fragmentary cross sectional view taken through the handle end of a golf club, showing the improved score recording means associated therewith.

Figure 2 is a fragmentary side elevation of the upper portion of the golf club, showing improved details of the invention.

Figure 3 is a side elevation of the main details of the invention, which are adapted to be positioned within a compartment in the golf club handle.

Figures 4 and 5 are cross sectional views taken on their respective lines in Figure 6 of the drawings.

Figure 6 is an enlarged fragmentary cross sectional view taken through operating details of the improved score recording means.

Figure 7 is a side elevation of a modified form of this invention, showing it as it will appear upon the handle portion of a golf club.

Figure 8 is a cross sectional view taken through the form of invention illustrated in Figure 7.

Figure 9 is the upper or movable part of

the improved score recording means as illustrated in Figures 7 and 8.

Figure 10 is a cross sectional view taken substantially on the line 10—10 of Figure 8.

Figure 11 is a cross sectional view showing the manner in which the movable portion of the invention may be secured in adjustable manner within the handle of the golf club.

Figure 12 is a detail of the upper end of the golf club handle as modified for this invention.

In the drawings, wherein for the purpose of illustration are shown preferred and modified forms of this invention, the letter A may generally designate the preferred form of invention which may include a shank B; handle C; and score recording means D. For the modified form of invention F, the same may include the shank portion G upon which the handle H is mounted, and the latter of which receives the improved score recording means K.

In the preferred form of invention, the shank B is of conventional structure, except that at the upper end thereof, a recess or pocket 15 may be provided, diagonally formed therein, which may receive a pencil 16 or the like in a secreted relation therein, so that when it is so placed the pencil will be entirely within the circumferential limits of the golf club. In the majority of instances the improved score recording means will be carried in connection with the putter, as the putter does not have to withstand any substantial usage, and the placing of the improved score recording devices in the handle of the putter does not weaken the putter for the purpose for which it is adapted.

The handle C is preferably of cylindrical formation, including a lower part 20 which is slipped over the upper end of the shank B. The lower part 20 may have an opening 21 therein as an entrance to the pencil receiving pocket 15, and a swingable flap 22 may normally close this opening. The handle C projects upwardly of the shank B, and provides a pocket or compartment 22 therein which receives the score recording mechanism D.

In the main the improved score recording mechanism D includes a frame 25, adapted to detachably support rollers or spools 26 and 27, and upon which spools the score recording sheet 28 is wound from one spool to

the other. The frame 25 is of novel formation, including upper and lower disc or plate portions 30 and 31 respectively, which are connected by a front wall 31^a which is 5 cavo-convex in cross section, and which provides a table or member over which the score sheet 28 is stretched so that a person may write thereon, and as will be subsequently described. A rear wall 33, primarily 10 provided for reinforcing purposes alone is disposed between the upper and lower disc portions 30 and 31, connected with the same.

The spools 26 and 27 are adapted to be supported in parallel relation by the discs 30 15 and 31 of the frame 25, and between the wall portions 31^a and 33 thereof, so that the sheet 28 reaches tangentially from one spool about the front surface of the arcuate plate or table portion 31, and then tangentially about the other spool, so that upon rotation of one 20 of the spools the sheet will be wound thereon from the other spool, and vice versa. As a means of supporting the spools 26 and 27, pins 35 and 36 may be carried by the lower 25 disc 31 in upwardly projecting relation therefrom, and slidably support thereon suitable spool plates 37; the plates 37 being supported above the disc 31 by means of springs 38. The lower ends of the spools 26 30 and 27 are provided with openings adapted to receive the upper ends of the pins 35 and 36, with the spools resting upon the plates 37 to compress the springs 38, and as is illustrated in the drawings. The upper ends of 35 the spools 26 and 27 are provided with key slots 40 therein, as is illustrated in Figures 5 and 6 of the drawings, adapted to receive the key-ends 41 provided upon the lower ends 40 of suitable pins 42 and 43 which are rotatably carried by the upper frame disc or plate 30. These pins 42 and 43 have collars 45 thereon which engage the plate 30 at opposite sides thereof, to prevent longitudinal movement of the pins 42 and 43, so that they are rotatably supported in the disc 30. The pins 42 and 43 are respectively provided 50 with pinions 46 and 47 thereon above the disc or plate 30, and relatively in different planes, which are adapted to be actuated at different times by rotatable cap member 50.

The cap member 50 is cooperably related 55 with the handle C, and in fact is a part thereof, including a lower diametrically reduced portion 51 which is adapted to fit within the upper end 52 of the handle C, suitable spring urged ball bearings 53 or the like being supported by the reduced end 51 at diametrically opposed points on the circumference thereof, which are adapted to engage in upper or lower grooves 54 and 55 which are provided inwardly of the inside circumference of the handle C adjacent the top thereof, so that the cap 50 may be supported in a desired position, whereby an internal gear 58 rigid therewith may be selec-

tively meshed with either the pinion 46 or the pinion 47.

It should be noted as an important feature of this invention that the handle C at one side thereof has an opening 60 therein, and the table portion 31 faces this opening so that the score sheet as it is drawn over the table 31 is visible through the opening 60, and a person scribes thereon a score or any other data desired. The provision of a score 75 sheet such as the score sheet 28 provides considerable material for writing, so that a great many games and other information may be jotted down and readily glanced at from time to time for reference purposes, as 80 it is sometimes desirable to do when comparing notes with those previously made. The opening 60 may be normally covered by a hinged flap, if desired, to protect the score sheet from becoming soiled, and the handle 85 C may be wrapped with leather or any suitable covering.

To operate the score recording means it is merely necessary for a person to rotate the cap 50, when it is in the position illustrated in Figure 1, and the score sheet will be continuously wound transversely of the opening 60, for the purpose of jotting down any data, such as the condition of weather, names of opponents, scores, or the like. If 90 it is desired to refer to some previously written portion of the score sheet, it is merely necessary for the person to pull outwardly on the cap 50, and the balls 53 will be withdrawn from the lower groove 55, into 100 the upper groove 54, and in this instance the internal gear 58 will then mesh with the upper pinion 47 and upon rotation of the cap 50 of the spool 27 will be rotated 110 for reversing the winding of the score sheet 115 from the spool 26 to the spool 27.

Referring to the modified form of invention F, the shank G is of ordinary formation, although upwardly thereon the same 110 may be reduced, to be disposed in the lower socket opening 70 provided by the handle body 72, which may be of metal or any approved material, and which has an opening 73 longitudinally provided in a side thereof. The handle body 72 just below the top edge 115 73^a thereof, and interiorly thereof is provided with an annular groove 75 into which the hook ends 76 of springs 77 may snap to retain the substantially cylindrical shaped score supporting member 78 in position within the pocket or compartment 79 provided in the handle body 72.

In detail the score sheet supporting member 78 of the recording means K includes 120 the tubular body portion 85 which depends within the compartment 79, and which receives thereabout in circumferential relation thereon a sheet 86 which may be provided with indicia 87 pertinent to the keeping of 125 the score of a golf game and which indicia 130

and the blanks for entering the scores are visible through the longitudinal opening 73 provided in the side of the handle H. At its upper end the body 85 has a head portion 88 integral therewith, provided with an annular shoulder 89 which contacts the upper end of the handle H when the score recording member 78 is in position. The head 88 is provided with lateral diametrically opposed recesses 91 therein, and into which the spring shaped snap members 77 are adapted to spring when the score recording member 78 is being removed or placed with respect to the pocket of the handle.

15 As is illustrated in Figures 7 and 8 of the drawings the handle body 72 may be exteriorly covered with protecting material 95, which may be leather spirally wound thereon, or any other covering, suitable provision being made in this covering 95 for the opening 73, so as not to obstruct the same, to permit the scribing of scores on the sheet 86 through the opening 73. A cover may be provided for the opening 73, which may 25 be a portion of the handle covering 95, if desired.

The operation of the device is obvious. It is preferred to provide three sets of the indicia 87 upon one of the score cards 86, and which may be successively moved into alignment with the opening 73 upon rotation of the head 88. The head 88 may be rotated with ease, since the hook ends 76 of the spring 77 always engage in the annular passageway 75, normally tending to prevent disconnection of the score recording structure K from the handle H.

From the foregoing description of this invention it is apparent that novel score recording means for golf clubs has been provided which will facilitate playing of the game, due to the ease with which the score may be set. For the purposes of the invention the body portion 85 of the score recording means K may be considered as a spool, and at any rate a tubular member upon which the score card or sheet is wound. The score sheet may be either of paper, or celluloid. It is to be noted with what ease the frame structure and spools of the score recording means may be removed from the handle C, and when in position they are retained in stable relation in the pocket 22 by the resting of the lower edge of the cap 55 against the top wall 30 of the frame 25.

Various changes in the shape, size, and arrangement of parts may be made to the form of invention herein shown and described, without departing from the spirit 60 of this invention or the scope of the claims.

I claim:

1. In a device of the class described the combination of a support having a pocket therein and a side opening communicating 65 with said pocket, a frame detachably sup-

ported within the pocket, a pair of spools rotatably and detachably supported by the frame, a score recording sheet wound from one spool to the other, a cap rotatable at the upper end of the support, and gear means 70 carried by the cap and by said spools by means of which said spools may be selectively rotated for winding or unwinding the score sheet with respect thereto.

2. In a score recording means of the class described a golf club having a handle provided with a pocket and with a lateral opening into said pocket, spools rotatably supported in said pocket, a score recording sheet wound on said spools and having portions 75 visibly disposed with respect to the opening in said handle, a single cap rotatable upon said handle; and gear means associated with said spools and with said cap by means of which the cap may be selectively positioned 80 and moved for rotating either of said spools to wind or unwind said score sheet with respect thereto.

3. In a device of the class described the combination with a golf club including a 90 handle having a compartment longitudinally therein and an elongated opening for said pocket, a frame supported by said pocket including upper and lower walls and an arcuate front wall supported in exposed relation 95 with respect to the opening in said handle, spools rotatably supported by the upper and lower walls of said frame, a score recording sheet wound on said spools and drawn across the front surface of said front wall in visible 100 and scribing relation with respect to the opening in said handle, and means formed as a part of the handle for rotating said spools.

4. In a device of the class described the combination with a golf club including a 105 handle having a compartment therein and an opening into said pocket, a frame supported by said pocket including upper and lower walls and an arcuate front wall supported in exposed relation with respect to 110 the opening in said handle, spools rotatably supported by the upper and lower walls of said frame, gears supported by said spools at different elevations above the upper ends thereof, a cap rotatable on said handle, a 115 gear fixed with said cap, and means for positioning the cap for rotation so that the gear of said cap will mesh in selective manner with the pinions of said spools one at a time.

5. In a device of the class described the 120 combination of an elongated handle having a pocket therein opening at an end of the handle, said handle along said pocket having an elongated opening thereto, a cap revolvably positioned in the open end of said handle to 125 enclose the pocket thereof at said end, record supporting means movably mounted in the pocket, and means connecting the record supporting means with the cap for movement of the former upon movement of the 130

4
latter to move the former across the elongated opening of said pocket.

6. In a device of the class described the combination of an elongated handle having a pocket therein opening at an end thereof, said handle along said pocket providing an elongated opening, a cap revolvably positioned in the open end of said pocket for closing said open end of the pocket, said cap being rotatable in the open end of the pocket and slidabie longitudinally of the pocket, movable record supporting means in the pocket visible thru the elongated opening therein, and means carried by the cap of the handle and by said record supporting means adapted to permit selective rotation of the latter in either direction according to the longitudinal disposition of the cap along said handle and the rotation thereof in the proper direction.

7. In a device of the class described the combination of a handle having a longitudinal pocket therein opening at an end of the handle, said handle along said pocket having an opening therein, a rotatable cap mounted in the open end of the pocket having an internal gear, means for sliding the cap longitudinally along the pocket to position the

internal gear in a plurality of different positions along the pocket, a plurality of spools 30 revolvably located in the pocket, independent gear means for said spools, and record supporting means carried by the spools trained from one to the other and adjusted to be wound on the spools selectively in either direction, said cap being adapted to be moved longitudinally of the pocket to selectively engage either of the gear means of the said spools at different times.

8. In a score recording means of the class 40 described, a golf club having a handle provided with the top thereof hollowed out to provide a pocket, and the top of the handle being open to the pocket, and the handle along a side, longitudinally thereof having a 45 slot to expose the pocket, a cap rotatably mounted in the open top of the pocket, a spool connected with the cap for rotation therewith, the spool extending downwardly into the pocket in spaced relation with the 50 inner surfaces of the pocket, and a score recording sheet on said spool in facing relation with the slot in the handle, and movable with the spool to expose various portions 55 thereof to the slot.

JAMES F. EGGLESTONE.
